UNITED STATES PATENT OFFICE.

WILLIAM S. SANBORN, OF NEW YORK, N. Y., ASSIGNOR TO SANBORN SECTIONAL WEIGHT CO., INC., OF NEW YORK, N. Y., A CORPORATION OF NEW YORK.

SASH WEIGHT.

1,424,592.

Specification of Letters Patent. Patented Aug. 1, 1922.

Application filed July 19, 1921. Serial No. 435,800.

To all whom it may concern:

Be it known that I, WILLIAM S. SANBORN, a citizen of the United States, and resident of the borough of Manhattan, city, county, 5 and State of New York, have invented certain new and useful Improvements in Sash Weights, of which the following is a specification.

My invention relates to sash-weights and 10 more particularly to that type which are commonly referred to as sectional sash-weights and generally comprise weight members adapted for interlocking with one another to provide the required weight. Be- 15 cause of the characteristics of sash-weights in general, it is desirable to construct the same as cheaply as possible and yet in a manner to provide the desired weight and efficiency of operation. With this in mind, 20 the manufacturers of sash-weights have generally utilized the cheapest materials obtainable, such as scrap-iron, the most common practice being to cast said sash-weights of such scrap-iron. Such sash-weights are, 25 however, extremely brittle, and in the case of sectional sash-weights made therefrom, result in a weight which, while it is eminently satisfactory in all other respects, is weak at its opposite ends because of the con- 30 necting devices which must be located thereat for connecting individual weights in series thereat. At the points mentioned the sectional sash-weights, during shipment and in handling, are more or less easily broken, 35 and through the resultant destruction of the connecting devices, are rendered useless for the intended purpose, and consequently represent a loss to the manufacturer, dealer or purchaser. The particular purpose of the 40 present invention is to overcome these objections in a novel and simple manner by pro- viding a sash-weight which includes, as an inherent property, all of the rigidity and mass necessary to provide the required 45 weight and in which the connecting means are incorporated in a manner to overcome any weakness and to prevent breakage there- 50 at. My invention will be fully described hereinafter and the features of novelty will be pointed out in the appended claims.

Reference is to be had to the accompanying drawings, which illustrate an example of my invention without defining its limits, and in which Figure 1 is an elevation of the 55 sash-weight showing several sections joined

together; Fig. 2 is an elevation of a single weight partly in section; Fig. 3 is an end view thereof, and Fig. 4 is a cross-section on the line 4—4 of Fig. 2.

As shown, the sash-weight comprises a 60 body 5 which may be of any suitable cross- sectional shape and axial length and is pref- erably cast of scrap-iron; at its one end the body 5 is continued in the form of integral spaced extensions 6 which define a space 7 65 bridged or spanned at an intermediate point by a cross-bar 8 which also comprises an in- tegral part of the weight, said extensions 6 and cross-bar 8 being formed by casting in a suitable mold. At its opposite end the 70 weight is provided with a connecting device whereby the sash-weights are coupled to- 75 gether in sections and which, generally speaking, is in the form of a hook 9 suitably constructed for insertion into the space 7 75 and co-operating with the cross-bar 8 to sus- 80 pend one weight from another. In the pres- ent invention the hook 9 is constructed of 85 wrought or malleable iron or of any other metal or material which is not brittle and 90 possesses an inherent rigidity correspond- 95 ing, at least, to that of the body 5. In the preferred form the hook 9 is of rectangular flat form and has a major width approxi- 100 mately equal to the cross-sectional dimen- 105 sion of the body 5 in at least one direction; as shown in the illustrated example, the hook 9 extends into the body 5 and is pro- 110 vided with an aperture 10 through which the cast-iron or other material of which the body 5 is constructed extends in the form of an integral bar 11. This result is secured by casting the body 5 about the hook 9, it being understood that the aperture 10 and bar 11 are intended to be representative of 115 equivalent means whereby a separation of the hook 9 from the body 5 under pulling strains is resisted. The hook 9 extends into the body 5 only to the extent necessary to secure a rigid connection, it being under- 120 stood that the combination of said hook and body is effected, as previously indicated, by casting the latter about the former, a most intimate and reliable union between the hook and body being secured in this way 125 and the operation of connecting the same being reduced to the simplest form and made coincident with the construction of the body.

The hook 9, because of its physical char- 130 acteristics and because of its inherent flexi- 135

bility, is not itself easily fractured or broken and at the same time, when coupled to another weight section, and because of these properties, absorbs strains and shocks which 5 otherwise would be communicated to the extensions 6 and tend to break the same. The recognized weaknesses of sash-weights of the type in question are thus overcome in an efficient and simple manner and the possibility 10 of breakage is reduced to a minimum.

In practice the sash-weights are utilized 15 in the recognized manner by attaching the sash-cord to the cross-bar 8 of the terminal section and coupling such additional sections 15 to said terminal section and to each other as may be necessary to provide the desired counterbalance of the particular window-sash in question.

With the present invention, in which the 20 danger of breakage at the connections between weight sections is eliminated, it is possible to construct the weight sections in the most desirable axial lengths and to make not only the body itself substantially immune 25 against injury but also to construct the connecting devices in a manner to render them practically indestructible under all ordinary conditions; that is to say, the number of 30 units which may be required to provide the desired mass of weight is of no consequence, as the connecting operation may be repeated as often and as carelessly as possible without danger of breakage of said connecting devices.

35 The present invention practically eliminates the waste resulting from breakage of the sash-weight sections and reduces the loss of time incident to replacement because of breakage on the job to a minimum point.

Various changes in the specific form 40 shown and described may be made within the scope of the claims without departing from the spirit of my invention.

I claim:

1. A sectional sash-weight comprising a 45 body of cast-iron provided at one end with integral coupling means, a relatively flat coupling hook of malleable iron located at the other end of said body and extending into the same to an extent which corresponds 50 to a fractional part of the axial length of said body, said malleable iron coupling hook having a major width corresponding to the cross-sectional width of the body in at least one direction and means within said body extending transversely to said major width of 55 said malleable iron hook whereby separation of the latter from said body is resisted.

2. A sectional sash-weight comprising a 60 body of cast-iron provided at one end with an integral coupling means, a coupling hook of malleable iron located at the other end of 65 said body and extending into the same to an extent which corresponds to a fractional part of the axial length of said body, said hook having a major width corresponding to the cross-sectional width of said body in at least one direction and being provided with an aperture extending through said hook transversely to said major width at an intermediate point; and a bar comprising an integral part of said body and extending through and completely filling the aperture 70 of said hook.

In testimony whereof I have hereunto set 75 my hand.

WILLIAM S. SANBORN.
